US0D1029457S

(12) **United States Design Patent** (10) Patent No.: **US D1,029,457 S**
(45) Date of Patent: ** Jun. 4, 2024

(54) **HIKING SHOE**

(71) Applicant: **DECATHLON**, Villeneuve d'Ascq (FR)

(72) Inventor: **Pierre Duquenoy**, Villeneuve d'Ascq (FR)

(73) Assignee: **DECATHLON**, Villeneuve d'Ascq (FR)

(**) Term: **15 Years**

(21) Appl. No.: **29/840,990**

(22) Filed: **Jun. 2, 2022**

(30) **Foreign Application Priority Data**

Dec. 3, 2021 (EM) 008786818-0009

(51) **LOC (14) Cl.** **02-04**

(52) **U.S. Cl.**

USPC **D2/900**; D2/902; D2/957; D2/960

(58) **Field of Classification Search**

USPC D2/896, 900, 902, 904, 905–912, D2/919–925, 929–931, 935–960, 969–978
